UNITED STATES PATENT OFFICE

2,383,674

PROCESS FOR PRODUCTION OF SODIUM BICARBONATE

Sidney G. Osborne, Saint Davids, Ontario, Canada, assignor to Hooker Electrochemical Company, Niagara Falls, N. Y., a corporation of New York

No Drawing. Application August 21, 1941,
Serial No. 407,756

2 Claims. (Cl. 204—87)

My invention relates more particularly to a process for production of sodium carbonate and bicarbonate by reaction of sodium hydroxide with carbon dioxide, and has for its object to produce the carbonate or bicarbonate in solid form from sodium hydroxide produced in electrolytic cells, with high yield thereof and without any evaporation step.

The crude product or effluent from caustic soda-chlorine cells is in general a liquor containing about 9½ per cent NaOH. Such cells are operated upon brine that has been made up at ordinary temperatures and contains about 290 grams of NaCl per liter, and usually show a yield or current efficiency of about 90 per cent. In Patent No. 2,173,986, there is disclosed a method of heating brine to 60° to 90° C. and resaturating it at these temperatures. Brine that has been saturated in this manner contains 310 to 325 grams of sodium chloride per liter. In Patent No. 1,866,065, there is disclosed an electrolytic alkali-chlorine diaphragm cell, which, when supplied with brine that has been saturated while hot in accordance with patent No. 2,173,986, produces an effluent containing 11 to 12 per cent NaOH. When producing 11 per cent NaOH solution, which is preferred practice, the current efficiency of this cell is ordinarily 95 per cent. The relatively concentrated product and high efficiency obtainable from cells constructed and operated in accordance with these patents will hereinafter be considered as typical of best modern practice and referred to accordingly, to distinguish these results from those characteristic of general practice. It is desirable, and one of the objects of my invention, to be able to adapt the cells of best modern practice to the production of sodium carbonate and bicarbonate.

It is known that alkali metal carbonates can be produced from electrolytic cell effluent by admitting carbon dioxide directly to the cathode compartment of the cell. In the case of the electrolytic cell and process illustrated and described in Hargreaves-Bird British Patent No. 18,039 of 1892, this is accomplished by admitting steam and gases containing carbon dioxide directly to the cathode compartment of the cell. This compartment becomes completely filled with an atmosphere of the gases, so that the sodium hydroxide produced in the cell comes into contact with the carbon dioxide as fast as formed. The efficiency of such a cell is typically 88 per cent and, as the contact of the hydroxide with the CO₂ is imperfect, the product is mostly the carbonate. The concentration of the hydroxide must be presumed to be of the order of that mentioned above as characteristic of the early art or later general practice.

Hence the cell effluent is quite unsaturated and as will be shown by example, the carbonation products are in solution. In the cell of the Patent No. 1,866,065, the cathode compartment is normally almost completely filled with effluent and this is one of the conditions which give this cell its high efficiency. To replace this liquid with an atmosphere of CO₂ would impair the efficiency of the cell. It would of course be possible to bubble CO₂ through the cathode compartment, but since this compartment is not designed for this purpose the reaction would be incomplete. Moreover, the hydrogen evolved in the cell, which is a valuable by product, would be contaminated by CO₂.

It has also been proposed in Craney Patent No. 552,955, 1896, and Suchy, Patent No. 1,477,086, 1923, to produce precipitated alkali metal bicarbonate by reacting carbonate, produced in the cathode compartment of an electrolytic cell, with CO₂. For this purpose, the filtrate remaining after the removal of the precipitated bicarbonate, containing chloride and residual carbonate and bicarbonate, is returned to the cathode compartment of the cell, where the bicarbonate reacts with fresh caustic alkali produced in the cell and is converted to carbonate. This is then reacted with CO₂ as before. In the process of the Craney patent the solution of alkali produced in the cell must be presumed to be of the concentration characteristic of the art of that time. In 1896 electrolytic alkali chlorine cells were quite primitive, by modern standards, and the concentration of caustic alkali even lower than the lowest modern practice. In fact, it was commonly of the order of 6 to 6½ per cent. The carbonate and bicarbonate produced from such solution would be of a correspondingly low concentration. A considerable part of the bicarbonate would be in solution. Alkali metal carbonate and bicarbonate react with chlorine to form water, the hypochlorite of chloride and the chloride, with liberation of CO₂. To recycle any considerable quantity of alkali metal carbonate or bicarbonate to the anode compartment of the cell would ruin the efficiency of the cell, destroy its anodes and contaminate the product. It will be shown later by example that, even if Craney produced in his cells sodium hydroxide corresponding to a 9½ solution, the bicarbonate remaining in solution after precipitation of bicarbonate in accordance with his process would be far greater than could be tolerated in the anode compartment of the cell.

The Suchy patent has to do with potassium bicarbonate, which is considerably more soluble than sodium bicarbonate, so that even when precipitating potassium bicarbonate by carbonation

of a saturated solution of potassium hydroxide and potassium chloride, a large part of the bicarbonate remains in solution. Thus Suchy says that his catholyte solution, which is the mother liquor remaining after saturation and carbonation as far as possible to the bicarbonate, contains 240 grams of potassium chloride and 140 grams of potassium bicarbonate per liter. If the mother liquor of Suchy were to be returned to the anode compartment of the cell, the bicarbonate in it would take up nearly half the chlorine liberated.

This is why in these processes the filtrate is necessarily returned to the cathode compartment. But as the fresh chloride is supplied to the anode compartment of the cell in solution, it brings in water with it. Water is of course necessary for production of the caustic alkali and some of the water is used up in the process; nevertheless the quantity brought in with the chloride is far greater than that used up. In the processes of the Craney and Suchy patents, the water therefore builds up in the system. Moreover, as only about one-half of the chloride is decomposed at each passage through the cell, the chloride likewise builds up in the system. Unless water were removed in some way the bicarbonate solution would become weaker and weaker, until no bicarbonate would be precipitated at all. The excess water cannot be thrown away as the values carried by it in the form of alkali metal chloride, carbonate and bicarbonate are too great to be allowed to go to waste. An evaporation step not mentioned in these patents is therefore an essential part of these processes. The processes of these patents could not be carried out in the cell of Patent No. 1,866,065 even if it were desirable to do so (which it is not), without impairing its efficiency.

I have found that it is unnecessary to disturb the operation and reduce the efficiency of the cell by reacting the caustic alkali with carbon dioxide or the bicarbonate in the cathode compartment of the cell itself, as in the processes of the three prior art patents referred to. On the contrary, it is far preferable to remove the effluent and carbonate it outside the cell, thus avoiding any interference with the normal operation of the cell. When this is done the caustic alkali can, if desired, be carbonated largely to the bicarbonate in a continuous operation. If the caustic alkali be that of sodium, and if the carbonation is carried out in an efficient absorption apparatus, very little carbonate need remain. If the caustic soda solution is brought to saturation by addition of sodium chloride before or after carbonation (preferably before), a very large part of the bicarbonate will be in the precipitate and only a negligible part will remain in the solution. This is especially true if the solution was originally of the relatively high concentration characteristic of best modern practice. In fact, I find that under these conditions the carbonation products remaining in the solution after removal of the precipitate are well within the limits that can be tolerated in the anode compartment of the cell. After removal of the precipitated bicarbonate I therefore recycle the filtrate, not to the cathode compartment of the cell in accordance with the practice of the prior art, but to the anode compartment. Since the water thus recycled replaces water that would otherwise be introduced with the brine, there is no building up of water in the system and the need for an evaporation step is eliminated. Moreover, the sodium chloride carried through the cell undecomposed is recycled

at the same time. It is only necessary to add water and sodium chloride in quantity sufficient to supply the water and chloride decomposed in the cell. In this way I am able to produce sodium bicarbonate in solid form, from the effluent of electrolytic caustic soda-chlorine cells, without any expensive evaporation step, and with very high yield, especially if the effluent be of high concentration, such as is produced in accordance with best modern practice.

If sodium carbonate is the product wanted, this is produced from the bicarbonate by roasting. In that case the CO_2 driven off is of course recycled.

15 The composition of the effluent of best modern practice and that of general practice are as follows:

	Best modern practice, weight percent	General practice, weight percent	Best modern practice, mols	General practice, mols
20				
NaOH	11	94	2.0	2.0
NaCl	15%	13%	1.92	1.94
25 H ₂ O	73%	77	29.70	36.00

It will be seen from these figures that the effluent of best modern practice is considerably more nearly saturated than that of the early art. The bearing of this upon my invention will appear from the examples to be given later.

30 The reaction of CO_2 with NaOH is as follows:

35 It will be seen from these reactions that Na_2CO_3 is an intermediate product in the carbonation of NaOH and that water is formed in the first part of the reaction and taken up again during the 40 second part. This is one of the reasons why the proportion of the Na_2CO_3 that is precipitated is so much less than the proportion of NaHCO_3 that is precipitated.

The carbonation of weak cell effluent in accordance with the Hargreaves-Bird process may be expressed as follows:

50 The Na_2CO_3 of this reaction will be entirely in solution. This will be shown later by an example.

The carbonation of the weak Na_2CO_3 solution of Equation 3 in accordance with the Craney patent may be written as follows:

A very considerable part of the NaHCO_3 of this reaction will be in solution, as will be shown later by example.

60 The carbonation of the weak cell effluent of the prior art, saturated by addition of NaCl thereto, with care to avoid going beyond saturation with NaCl , may be written as follows:

The NaHCO_3 of this reaction will be largely in the precipitate. This again will be illustrated by example.

70 The carbonation of the strong cell effluent of recent practice, after saturation by addition of NaCl , may be written as follows:

The NaHCO_3 of this reaction will be almost entirely in the precipitate, only a negligible proportion remaining in the filtrate. This will likewise be shown by a specific example.

Example I.—9½ per cent NaOH solution containing 13½ per cent NaCl was carbonated to Na_2CO_3 in accordance with Reaction 3. The composition of the product in parts by weight was as follows:

	Solids	Filtrate
Na_2CO_3	None	150.0
NaHCO_3	do	21.8
NaCl	do	181.6
H_2O	do	1,000.0

This result is typical of the Hargreaves-Bird process and shows why the product is a solution.

Example II.—The product of Example I was carbonated as far as possible to NaHCO_3 in accordance with Reaction 4. The composition of the resulting product was as follows:

	Solids	Filtrate
Na_2CO_3	None	94.0
NaHCO_3	115.0	68.0
NaCl	3.8	178.0
H_2O	None	1,000.0

This result is typical of the Craney process. The analysis of the filtrate shows that it contains a substantial part of the product and proves that the filtrate remaining after removal of the precipitated solids in this process is far too alkaline to be recycled to the anode compartment of the cell, and must therefore be recycled to the cathode compartment, necessitating an evaporation step to prevent accumulation of water and NaCl in the system.

Example III.—9½ per cent NaOH solution was brought to saturation by addition of NaCl , care being exercised to avoid adding more NaCl than just sufficient for saturation. The solution was then carbonated as far as possible to NaHCO_3 , in accordance with Reaction 5. The composition of the product was as follows:

	Solids	Filtrate
Na_2CO_3	20.9	3.08
NaHCO_3	208.0	7.50
NaCl	None	301.90
H_2O	None	1,000.00

This represents a yield of Na_2CO_3 and NaHCO_3 amounting to 84.2 per cent of the theoretical yield, based on the current supplied to the cell, assuming the efficiency of the latter at 90 per cent, or a yield of 80 per cent in the precipitate. The filtrate of this example is low enough in Na_2CO_3 and NaHCO_3 to be recycled to the anode compartment of the cell without seriously affecting its efficiency.

Example IV.—11 per cent NaOH solution saturated by addition of NaCl , with care to avoid an excess of NaCl , was carbonated as far as possible to NaHCO_3 in accordance with Reaction 6. The resulting composition was as follows:

	Solids	Filtrate
Na_2CO_3	37.06	1.57
NaHCO_3	236.89	9.77
NaCl		298.00
H_2O		1,000.00

This represents a yield of Na_2CO_3 and NaHCO_3

amounting to 93.0 per cent of the theoretical yield, based on the current supplied to the cell, assuming the efficiency of the cell at 95 per cent as before, or a yield of 89 per cent in the precipitate.

5 The filtrate is obviously fit to be recycled to the anode compartment of the cell without appreciably affecting its efficiency.

A comparison of this example with Example III shows that the increased concentration of 10 NaOH obtainable by best modern practice results in an increase in yield of Na_2CO_3 and NaHCO_3 in the precipitate from 80 per cent to 89 per cent. This example represents what I consider good practice of my invention.

Example V.—11 per cent NaOH solution, saturated by addition of NaCl with care to avoid an excess thereof, was carbonated as far as possible to NaHCO_3 in accordance with Reaction 6 as in the previous example, except that the reaction 20 was carried on under a pressure of 2 mm. of mercury, in order to promote absorption of the CO_2 . The analysis of the product was as follows:

	Solids	Filtrate
25		
Na_2CO_3		24.8
NaHCO_3		2.8
NaCl		268.0
H_2O		6.23
		288.40
		1,000.00

30 This result represents a yield of Na_2CO_3 and NaHCO_3 amounting to 96 per cent of the theoretical yield, assuming the cell efficiency at 95 per cent as before, or a yield of 92.7 per cent in the precipitate.

35 A comparison of this result with that of the preceding example shows that a slight pressure assists the absorption of CO_2 sufficiently to raise the yield of Na_2CO_3 and NaHCO_3 in the precipitate from 89 per cent to 92.7 per cent. This example 40 represents what I at present consider best practice of my invention.

It should be noted that the yield of 92.7 per cent of solid dry Na_2CO_3 and NaHCO_3 obtained in 45 Example V compares favorably with the yield of 88 per cent of Na_2CO_3 obtained by the Hargreaves-Bird process. Moreover, in the Hargreaves-Bird process, as shown above, the product is a solution and the cost of its recovery is a serious item of expense, which it is one of the objects of my invention to avoid.

In carrying out the carbonation step of my process the liquid may be sprayed downward through an atmosphere of CO_2 ; or the CO_2 may be bubbled 55 through successive batches of the liquid so that a very large excess of CO_2 will be contacted very vigorously with each batch as it nears the finish of the carbonation, in order to carry the carbonation as nearly as possible completely to the bicarbonate. Pressure in excess of the 2 mm. of mercury of Example V may also be used.

In carrying out the saturation of the cell effluent with sodium chloride, the addition of excess chloride beyond that which will go into solution can be avoided by passing the liquid upward 65 through a bed of finely divided salt at a velocity below that at which salt is carried upward.

By my process I am therefore able to produce dry sodium bicarbonate from the effluent of caustic soda-chlorine cells, without the expensive evaporation step heretofore believed to be unavoidable, beyond the slight cost of drying; and, by taking advantage of the high concentration of NaOH in the effluent of the best modern cells, I am able to do so not only without any sacrifice in yield, but with an actual improvement in that respect.

This application is a continuation-in-part of application Serial No. 329,738, for processes for production of alkali metal chlorates and more particularly potassium chlorate, filed April 15, 1940, by me jointly with Robert B. Lowry and Walter S. Beanblossom, now Patent No. 2,287,061.

I claim as my invention:

1. The cyclic process for production of precipitated sodium bicarbonate of high purity and with a high overall yield thereof and avoidance of any separate steps for evaporation of water or filtration of caustic soda solution which comprises supplying a substantially saturated solution of sodium chloride to the anodic zone of an electrolytic diaphragm cell and therein electrolyzing it to decompose a part of the sodium chloride, thereby producing in the cathode zone of the cell an unsaturated solution containing caustic soda and sodium chloride; removing the solution from the cell; passing the solution through a bed of sodium chloride, thereby bringing the solution to substantial saturation with respect to sodium chloride and caustic soda, while leaving behind any insoluble impurities carried by the solution or sodium chloride; passing carbon dioxide into the saturated solution until the caustic soda therein is carbonated as far as practicable to sodium bicarbonate; filtering out from the solution the resulting precipitated sodium bicarbonate; adding water to the filtrate to replace the water decomposed in the electrolysis step; resaturating the re-

sulting solution; and recycling the augmented solution to the anodic zone of the cell.

2. The cyclic process for production of precipitated sodium bicarbonate of high purity and with a high overall yield thereof and avoidance of any separate steps for evaporation of water or filtration of caustic soda solution which comprises supplying a substantially saturated solution of sodium chloride to the anodic zone of an electrolytic diaphragm cell and therein electrolyzing it to decompose a part of the sodium chloride, thereby producing in the cathode zone of the cell an unsaturated solution containing caustic soda and sodium chloride; removing the solution from the cell; passing the solution upwards through a bed of sodium chloride at a velocity below the predetermined velocity at which particles of salt are carried upward, thereby bringing the solution to substantial saturation with respect to sodium chloride and caustic soda, while leaving behind the insoluble impurities carried by the solution or sodium chloride; passing carbon dioxide into the saturated solution until the caustic soda therein is carbonated as far as practicable to sodium bicarbonate; filtering out from the solution the resulting precipitated sodium bicarbonate; adding water to the filtrate to replace the water decomposed in the electrolysis step; resaturating the resulting solution; and recycling the augmented solution to the anodic zone of the cell.

SIDNEY G. OSBORNE.
